Primary Examiner — Catheri Oliver-Garcia(74) *Attorney, Agent, or Firm* — Christensen O'Connor Johnson Kindness PLLC(57) **CLAIM**

The ornamental design for an illuminated semiochemical fixture, as shown and described.

DESCRIPTION

FIG. 1 is a front, top and side perspective view of the illuminated semiochemical fixture in accordance with the present design;

FIG. 2 is a front view of the illuminated semiochemical fixture shown in FIG. 1, which is the same as the rear view;

FIG. 3 is a left side view of the illuminated semiochemical fixture shown in FIG. 1, which is the same as the right side view;

FIG. 4 is a top view of the illuminated semiochemical fixture shown in FIG. 1; and,

FIG. 5 is a bottom view of the illuminated semiochemical fixture shown in FIG. 1.

The broken lines which define the bounds of the claimed design form no part thereof.
